UNITED STATES PATENT OFFICE.

JAMES R. COE, OF WATERBURY, CONNECTICUT, ASSIGNOR TO THE AMERICAN BRASS COMPANY, OF WATERBURY, CONNECTICUT, A CORPORATION OF CONNECTICUT.

ROLLING MILL.

Application filed July 8, 1925. Serial No. 42,183.

This invention relates to rolling mills, and has for an object to provide improved means to obtain the necessary stiffness with the use of rolls of comparatively small diameter. 5 It is also an object of the invention to so mount the working rolls and the stiffening and supporting means therefor that one of the rolls and its stiffening means may be adjusted as a whole or as a unit relative to 10 the other working roll to secure the required relative adjustment between the rolls.

It is a further object of the invention to so construct the mounting and stiffening means for the working rolls that they may be 15 mounted in the standard housings used in this type of device, and therefore, rolls provided with my improved stiffening and supporting means may be substituted for larger rolls mounted in the housings without re- 20 constructing the housings.

With the foregoing and other objects in view, I have devised the construction illustrated in the accompanying drawings and which in its preferred construction, comprises a pair of working rolls each of which is backed and supported by a pair of backing and supporting rolls reduced in diameter at spaced points to provide an interrupted 25 surface to engage the working rolls. The reduced portions are mounted in and supported by journal blocks forming bearings for these reduced portions of the backing rolls, which journal or bearing blocks are mounted in heavy castings so designed as to 30 be mounted in the rolling mill frames or housings. These elements are so constructed and arranged that one unit consists of one of these castings, two backing rolls and one working roll, and one of these units is so 35 mounted that it is adjustable as a whole relative to the other unit in a vertical plane, this adjustment being secured by the usual means of lifting rods actuated by levers and counter weights or springs in conjunction 40 with the usual adjusting screws.

Referring to the accompanying drawings, Fig. 1 is a side elevation of a rolling mill comprising my improved construction.

Fig. 2 is a transverse vertical section 50 through the same substantially on line 2-2 of Fig. 1, but drawn to a larger scale.

Fig. 3 is an end elevation of the mill looking from the right of Fig. 1, and

Fig. 4 is a detail view showing one of the backing rolls in elevation and the bearings 55 and support therefor in vertical section.

In rolling mill practice frequently very high pressures are required and rolls to withstand these pressures and not yield or spring an objectionable amount must be of a very 60 large diameter, which makes them expensive and also difficult to handle. These larger rolls are also objectionable for certain work because, on account of the small angle at the rolling point between the rolls, it is difficult 65 to secure the required reduction in the metal being rolled.

To overcome these objections mills have been made with working rolls of relatively small diameter in order to secure a larger 70 angle at the rolling point between the rolls and give the required reduction, and these rolls have been backed or supported by means of separate idling rolls to prevent excessive springing of the working rolls and 75 to give the required strength, but as these backing rolls are supported in substantially the same way as the working rolls they must be of a large diameter to give the required strength and stiffness, and they require specially designed housings or frames. 80

I have found that by providing the backing rolls with separate bearings intermediate their lengths and mounting these bearings in a heavy casting to give the required strength and stiffness I can use relatively small working rolls and also relatively small backing rolls, and that I can mount these rolls and the supporting castings in the ordinary standard housings or frames. 90

In the accompanying drawings I have shown a mill involving my improved construction. In this mill 10 represents a pair of the usual housings or frames mounted on the usual supporting rails 11, on which they are longitudinally adjustable, but may be secured in adjusted position by any suitable means. Mounted in these housings is a pair of heavy castings 12 and 13 which extend longitudinally between the two housings. 100 In the present construction the lower casting is seated at its opposite ends in the housings and rests on the lower wall 14 of the opening 15 of the housings, while the upper casting 12 is guided at its opposite ends for 105 vertical movement in these openings, the

side walls of the openings forming guides for the casting to maintain it in proper position. These castings are of similar construction and are strengthened to give them the required vertical stiffness by the ribs 16, and they are also provided with lateral ribs 17 to give them the required lateral stiffness. These castings are recessed on their opposed sides to receive bearing blocks 18 for the 10 backing or supporting rolls 19, there being in the present construction two backing rolls for each working roll, as shown in Fig. 2, two above the upper roll 12 and two below the lower roll 13. These backing 15 rolls are reduced in diameter at suitable spaced points intermediate their lengths, as shown at 20, to provide bearings running in the bearing blocks 18 and also to provide an interrupted surface to the rolls which 20 gives a plurality of spaced surfaces 21 to engage the surfaces of the working rolls 33. By reducing the diameters of the backing rolls at the portions 20 the bearings are removed from the surface which engages the 25 working rolls, and therefore, the oil and grease which is required on these bearings is not carried to the surface of the working rolls where they would be transferred to the metal being rolled. This arrangement, 30 therefore, not only provides supporting bearings at suitably spaced distances throughout the length of the backing rolls, but these bearings are secured without contaminating the surfaces of the rolls with 35 grease. It will further be apparent that with this arrangement the backing rolls may be made of relatively small diameter as the strains are taken up by the heavy castings 12 and 13, which castings give the backing 40 rolls, and through the backing rolls the working rolls, the required stiffness. Thus the working rolls may be given any diameter which is the most suitable for the particular work to be performed having in mind the 45 desired angle between the rolls at the rolling space.

It is also preferred to provide caps 22 on the opposite sides of the rolls from the bearing blocks 18 in the reduced portions of the backing rolls, these caps being secured to the castings 12 and 13 by any suitable means such as the screws 23, these caps helping to retain the backing rolls in the castings. Bearing blocks 24 and 25 are provided for 55 the reduced necks 26 of the working rolls, and these blocks are also guided in the openings 15 in the housings.

The supports for the various rolls are so 60 constructed and arranged that each working roll, its backing rolls and the supporting casting therefor comprise a separate unit, and one of these units, the upper one in the present instance, is mounted so that it is adjustable as a whole relative to the lower unit 65 to give the required adjustments between the

two working rolls for rolling various thicknesses of metal and so forth. To accomplish this, in the present construction, the upper bearing blocks 24 are supported by the rods 27 which extend upwardly from below the 70 housing where they are supported by the usual lever and counterweights or heavy springs 28. These springs are mounted on a support 29 carried on the underside of the housing by the bolts 30 and bear at their 75 upper ends against collars 31 secured to the rods 27 and thus tend to lift these rods. These rods carry suitable nuts 32 which engage the lower sides of the blocks 24 and thus tend to lift the upper working roll 33, 80 the two backing rolls 19 therefor and the supporting casting 12 as a unit. The upward movement of this unit is controlled by the usual adjusting screws 34 mounted in the tops of the housings and engaging the castings 12. It will thus be apparent that the 85 springs 29 acting through the rods 27 maintain the upper working roll, the backing rolls, and the supporting casting therefor always in the same relative positions, and that 90 these elements by the coaction of the adjusting screw with these rods and springs allow adjustment of this unit as a whole and without changing in any way the relative positions of the elements of the unit, and further that this unit may be adjusted in a vertical plane relative to the lower working roll. The lower blocks 25 are provided to form 95 upper bearings for the necks of the lower working roll through which the rods 27 extend. Bolts 35 extend through and between the two bearings and carry springs 36 reacting at their opposite ends against these two bearings and tend to separate the same and hold the lower working roll in proper 100 position on its two backing rolls.

The rolls are driven from any suitable source of power, not shown. As shown in Fig. 1 the squared ends 37 of the working rolls are connected by suitable couplings 38 to the blocks 39 driven by any suitable means from the source of power. At their opposite ends the two working rolls have driving connection through the gears 40. The backing rolls for the respective working rolls are driven from the gears 40, but as the two backing rolls for each working roll must be driven in the same direction one of the backing rolls is driven by a gear 41 meshing with one-half of its driving gear 40 while the other backing roll is driven by a gear 42 meshing with the other half of the gear 40.

It will be apparent from the foregoing that with the construction and arrangement described I can use working rolls of relatively small diameter and can secure the necessary stiffness with the use of backing rolls of comparatively small diameter. Thus the use of excessively large rolls is not required. Furthermore by mounting the cluster or 125 130

- group of rolls in one big casting they can be adjusted as a whole, and the various elements are held in proper relation with each other with a minimum use of jointed parts.
- 5 6 By this construction change in the relative positions of the various elements under stress is reduced to a minimum.
- Having thus set forth the nature of my invention, what I claim is:
- 10 1. In a rolling mill, a working roll, a backing roll extending longitudinally of the working roll, said backing roll being reduced in diameter at spaced points throughout its length to provide spaced bearing surfaces to engage the working roll and support it throughout substantially its entire length, supporting bearings for the reduced portions of the backing roll, and a rigid support for the bearings.
- 15 2. In a rolling mill, a pair of working rolls, a pair of backing rolls for each working roll extending longitudinally thereof, said backing rolls being reduced in diameter at spaced points throughout their lengths to provide spaced bearing surfaces to engage the working rolls, supporting blocks for the backing rolls having bearings for the reduced portions of the rolls, and supports for the blocks.
- 20 3. In a rolling mill, a pair of spaced housings, a working roll between the housings, a pair of laterally spaced backing rolls extending longitudinally of the working roll, each backing roll being reduced in diameter at spaced points throughout its length to provide spaced bearing surfaces to engage the working roll and support it throughout substantially its entire length, supporting bearings for the reduced portions of said backing rolls, and a rigid support for said bearings extending between the housings and supported thereby.
- 25 4. In a rolling mill, a working roll, a backing roll for the working roll extending longitudinally thereof and reduced in diameter at spaced points throughout its length to provide spaced bearing surfaces to engage the working roll, supporting blocks for the backing roll having bearings for the reduced portions of said roll, and a support for the said blocks.
- 30 5. In a rolling mill, a working roll, a backing roll for the working roll reduced in diameter at a plurality of spaced points intermediate its length to give an interrupted surface to engage the working roll, bearings for the reduced portions of the backing roll to support the same, and a support for the bearings.
- 35 6. In a rolling mill, a working roll, a pair of backing rolls for the working roll, each backing roll being reduced in diameter at a plurality of spaced points intermediate its length to give interrupted surfaces to engage portions of the backing rolls to support the same, and a support for the bearings.
- 40 7. In a rolling mill, a working roll, a backing roll having a plurality of spaced bearing surfaces to engage and support the working roll throughout substantially the length thereof, supporting bearings for the backing roll engaging the same between said bearing surfaces, and supporting means for said bearings.
- 45 8. In a rolling mill, a working roll, a pair of backing rolls each having a plurality of spaced bearing surfaces to engage and support the working roll throughout substantially its entire length, a support, and bearings engaging the backing rolls between the said bearing surfaces to support said rolls and mounted in the support.
- 50 9. In a rolling mill, a working roll, a pair of backing rolls for the working roll, each backing roll being reduced in diameter at a plurality of spaced points intermediate its length to give interrupted surfaces to engage the working roll, bearings for the reduced portions of the backing rolls to support the same, a support for the bearings, and means for adjusting the rolls and the support vertically as a unit.
- 55 10. In a rolling mill, a pair of spaced housings, a working roll between the housings, a pair of backing rolls for the working roll each having a plurality of spaced bearing surfaces to engage the surface of the working roll to support said roll throughout substantially its entire length, a support mounted in and extending between the housings, and bearings for supporting the backing rolls engaging said rolls between the said bearing surfaces and mounted in the support.
- 60 11. In a rolling mill, a pair of superposed working rolls, a pair of backing rolls for each working roll, said backing rolls being each reduced in diameter intermediate its length giving an interrupted surface to engage the working rolls, bearing blocks having bearings for the reduced portions, supports for the blocks and means for adjusting one of the working rolls, its backing rolls and the support therefor as a unit relative to the other working roll.
- 65 12. In a rolling mill, a pair of spaced housings having transverse openings therein, a working roll between the housings, a backing roll for the working roll having a plurality of spaced bearing surfaces to engage and support the working roll throughout substantially its entire length, supporting bearings for the backing roll engaging it between said bearing surfaces, and a rigid support for said bearings extending between the housings and projecting at its ends into the openings therein so that it is supported by the housings.

13. In a rolling mill, a pair of spaced housings, a working roll mounted in the housings, a backing roll for the working roll extending longitudinally thereof and reduced in diameter at a plurality of spaced points intermediate its length giving an interrupted surface to engage the working roll throughout substantially its entire length, bearings for the reduced portions of the roll, 10 and a support for the bearings mounted in the housings.
14. In a rolling mill, a pair of spaced housings, a pair of working rolls mounted in said housings, a pair of backing rolls for 15 each working roll extending longitudinally thereof, said backing rolls being reduced in diameter at spaced points intermediate their lengths to give an interrupted surface to engage the working rolls throughout substantially their entire lengths, bearings for said reduced portions, supports for the bearings mounted in the housings, and means for adjusting one of the working rolls, its backing rolls and the support therefor in the housings as a unit relative to the other working roll.
15. In a rolling mill, a pair of spaced housings having transverse openings therein, a working roll between the housings, a pair
- of laterally spaced backing rolls for the 30 working roll extending longitudinally thereof, each backing roll having a plurality of spaced bearing surfaces to engage and support the working roll throughout substantially its entire length, supporting bearings 35 for each of the backing rolls engaging it between said bearing surfaces, and a rigid support for said bearings extending between the housings and projecting at its ends into the openings therein so that it is supported 40 by the housings.
16. In a rolling mill, a pair of spaced housings having transverse openings therein, a working roll between the housings, a 45 backing roll for the work roll extending longitudinally thereof, said backing roll being reduced in diameter at points intermediate its length to form a plurality of spaced bearings and provide a plurality of spaced bearing surfaces to engage the working roll, 50 supporting bearings for the bearings on the backing roll, and a rigid support for said supporting bearings extending between the housings and projecting at its ends into said openings so as to be supported by the housings.

In testimony whereof I affix my signature.

JAMES R. COE.
